UNITED STATES PATENT OFFICE

PHILIP N. BRAUN, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK

PRESSING MACHINE

Application filed July 3, 1924, Serial No. 724,045. Renewed June 13, 1929.

This invention relates to garment and laundry pressing machines and has for its object a particular simple and efficient mechanism for operating or controlling the operation of the movable pressing element or head by which it is impossible for the hands or fingers of the operator to become caught between the pressing elements during the closing of the press, and without the use of guards and the like.

The invention consists in the novel features and in the combinations and constructions hereinafter set forth and claimed and described. In describing this invention, reference is had to the accompanying drawings, in which like characters designate corresponding parts in all the views.

Figure 1 is a side elevation of the pressing machine embodying my invention.

Figure 2 is a fragmentary front elevation of parts seen in Figure 1.

Figure 3 is a side elevation of a modified form of a pressing machine.

Figure 4 is a fragmentary detail sectional view of the periodic clutch mechanism and contiguous parts.

Figure 5 is a detail view of the shiftable clutch section.

Figure 6 is a face view of the cam for holding the shiftable clutch section in its operable or "in" position during the opening movement of the press.

Figure 7 is a diagrammatic view of the wiring of the electro-magnet.

This pressing machine comprises generally cooperating pressing elements, one of which is movable toward and from the other, mechanism for applying pressure to the movable element, means for controlling the operation of said mechanism including an electro-magnet having a plurality of normally open, manually operable switches as push buttons in the circuit of the magnet, which switches automatically open so that both of the switches or push buttons must be operated to effect the application of pressure to the movable element or the closing of the press. The machine further includes means for controlling the actuation of the movable element during the opening movement thereof

independently of the electromagnet, after said switches have been but momentarily operated to close the circuit through the electromagnet when the machine is closed.

I have here illustrated my invention as applied to a garment or laundry press of the conventional type including a stationary lower pressing element or buck 1 and a movable pressing element or head 2, the buck 1 being mounted upon a bracket 3, which is supported on a frame 4, including legs or pedestals 5, 6.

The press head 2 is carried on the forward arm of the forwardly and rearwardly extending lever or yoke 7 which is pivoted between its ends at 8 to a standard 9 which is an extension of the rear leg 6 of the frame.

10 is a counterbalancing weight mounted on the rear arm of the lever 7, as shown in Figure 1. The power is applied to the head 2 through the lever 7 and toggle links 11 and 12 which are pivoted together at 13, the link 11 being pivoted at 14 to the rear arm of the lever 7 and the link 12 being pivoted at 15 to the frame near the lower end of the leg 6 and in a nearly vertical line with the pivot 8. The link 12 is in the form of a bell crank lever pivoted at its angle and one arm 16 extending forwardly and constituting a power arm or an arm to which the power is applied.

The link 11 includes sections which are compressible against the action of the spring 17. As the construction of such compressible links is well known, further description is thought to be unnecessary.

The mechanism for applying pressure to the head 2 in addition to the lever 7 and toggle links 11 and 12 includes a constantly running drive shaft 18, an intermittently movable driven shaft 19, a periodic clutch for connecting the driving and driven shafts including a section shiftable to its operative or "in" position by operator controlled means and to its ineffective or "out" position automatically.

The driving shaft 18 is an extension of the armature shaft of an electric motor 20 suitably supported by the frame below the table

or portion thereof on which the buck 1 is mounted.

The driven shaft 19 extends in a direction crosswise of the driving shaft 18 and is journaled in a suitable housing 21 supported by the frame beneath the table on which the buck is mounted and the clutch mechanism is also located in the housing 21.

The driving shaft 18 is here shown, as having a worm 22 thereon within the housing 21, this worm meshing with a worm wheel 23 mounted concentrically with the shaft 19 and rotatable relatively thereto.

The periodic clutch includes a shiftable clutch section 24 mounted on and keyed to the shaft 19 but slideable axially thereon, and pins 25 shiftable by the section 24 into holes 26 in the worm wheel 23. The pins 25 are tapered at their ends and the holes 26 are also tapered so that the pins readily release themselves from the wheel 23 when the force tending to hold the section 24 in its shifted position is discontinued. The pins 25 are guided in a guide ring 27 mounted adjacent to wheel 23, and the motion of the shiftable member 24 is transmitted to the pins through a pressure ring 28, through which the pins slide, and comparatively light springs 29 interposed between the pressure ring and the section 24. The ring 28 thrusts against shoulders 30 on the pins 25. In the event the pins 25 are not aligned with the holes 26 when the section 24 is shifted, the springs 29 will compress and these springs 29 will shift the pins into the holes 26 when the pins come into alignment with the holes 26. A main spring 31 shifts the clutch section 24 to its "out" position.

The clutch is shifted to its "in" position by a shifter arm 32 thrusting against the hub of the clutch section 24, this shifter arm being mounted on a rock shaft 33 journaled in the case 21 and having an operating lever 34 mounted thereon. This operating lever is angular, one arm portion thereof extending upwardly and having an arm 35 extending horizontally under the table on which the buck is mounted. The means for operating the arm 35, as here shown, consists of an electromagnet which in the present form of my invention is a solenoid 36 supported in a case 37 carried by the frame 4, the core 38 of the solenoid being connected by a pin-and-slot connection 39 to the arm 35 of the lever 34. Obviously, when the solenoid is energized, the core 38 will be pulled downwardly, and the lever 34 will be actuated to shift the clutch section 24 to the left, Figure 4, and carry the pins 25 into interlocking engagement with the worm wheel 23 which constitutes a drive wheel. The solenoid is controlled by two normally open manually operative switches 40, which may be operated by push buttons and which are connected in series in the circuit of the solenoid, the wires

41 and 42 of this circuit extending into a suitable junction box 43 carried by the frame. In the box 43 connection is made with the service wires.

The shaft 19 is connected to the power arm 70 16 in any suitable manner, and as shown in Figure 1, it is provided with an eccentric 44, which is connected by a link 45 to the power arm 16.

To close the press, both switches 40 must 75 be closed and held closed so that the solenoid 36 is energized to cause the core 38 to be pulled downwardly and thus actuate the lever 34 to move the shifter arm 32 to the left and shift the clutch section 24 to carry the pins 80 25 into interlocking engagement with the driving wheel 23.

If the operator holds the switches 40 closed, the press head 2 will be brought down to its fully closed position, it requiring a half 85 revolution of the shaft 19 to close the press and apply pressure thereto. If however, the operator releases either one or both of the switches 40, the press head will immediately stop. Thus the operator must keep both 90 hands busy while the press is closing, so that there is no possibility of his having either one of his hands between the pressing elements while the press is closing. Preferably to open the press but a momentary closing of 95 the switches 40 is required in order to shift the clutch 24 to its "in" position and means is provided for holding the clutch section 24 in its "in" position during the opening movement of the press. This means comprises a 100 cam ring 46 carried by casing 21 and arranged concentric with the shaft 19 and a follower 47 carried by the clutch section 24 and co-acting with the cam ring. Substantially one half of the cam ring is formed with the low 105 surface 48 and the other half with the high surface 49, these surfaces being substantially semi-circular.

When the press is open, the follower 47 is at the starting end of the low surface 48 and 110 during the closing movement of the head 2, the follower is spaced apart from this low surface and remains spaced apart therefrom as long as the operator holds both switches 40 closed.

The operator determines by the feel of the machine when the press is closed and releases either or both of the push buttons 40 when the press is closed. At the starting of the closing movement, the eccentric 44 is in its 120 position shown in Figure 1, and at the end of the closing movement, it is in the diametrically opposite position and remains in its diametrically opposite position while the press is held closed.

To open the press, both switches 40 are momentarily closed to momentarily energize the solenoid 36, so that the clutch section 24 is moved to its "in" position and during the initial part of the turning of the clutch sec- 125

tion 24, the follower 47 is carried on to the high part 49 of the cam and this high part of the cam holds the clutch in its "in" position while the shaft is making a half revolution back to the position shown in Figure 1.

The electric motor is merely a prime mover. It is connected in any suitable feed circuit and is constantly running while the machine is being used, it running idly after the press is opened and after it is closed. It performs work only during the closing of the press when the clutch sections are engaged and during the opening of the press when the clutch sections are engaged. During the opening movement, the work on the motor is momentary. The motor may be replaced by any other prime mover or by a pulley. The electric circuit in which the windings of the electro magnet are connected and also in which the push buttons or control switches 40 are connected may be connected in any suitable feed circuit of sufficient capacity to energize the magnet. For convenience, the circuit for the magnet is connected to the same service wires or feed circuit as those to which the motor is connected, although the energizing of the magnet is in no way co-ordinated with the operation of the motor since the motor is constantly running.

In Figure 3, I have shown a pressing machine with a different form of toggle mechanism, and in this machine, the head 2 and front arm of the yoke 7 substantially counterbalances the weight 10 and other parts connected to the rear arm of the yoke, so that the head stays in any position it is placed. In the machine shown in Figure 3, the operator preliminarily closes the press by pulling down on the handle 51 on the front end of the yoke 7 and the head being counterbalanced stays in this position. The operator then closes both switches 40, so that the power is applied to the power arm 52. This power arm is here shown as a lever pivoted at 53 between its ends and the motion of the lever transferred to the yoke 7 through toggle links 54 and 55 pivoted together at 56 and pivoted respectively at their ends to the rear arm of the yoke 7 and to the frame. The link 55 is preferably pivoted on the same pivot 53, that the power arm 52 is mounted on. The links 54 and 55 are so arranged that they are normally in an ineffective position, to apply pressure to the head 2, when the press is open, but are moved into effective position to receive and transmit the power of the lever 52 when the press has been preliminarily closed. The connections between the power lever 52 and the toggle comprises a link 57 pivoted at 58 to the rear arm of the power lever 52 and connected at its upper end to an extension 59 of the link 54 by a pin-and-slot connection 60.

When the press head is open or up, the link 57 extends rearwardly nearly horizontally

and hence will idle, if the power is applied to the lever 52 and this lever 57 will also idle until the toggle links 54 and 55 have been brought into a nearly straightened position or a position assumed when the head 2 has been brought down close to the buck 1. The construction and operation of the toggle linkage forms no part of this invention.

In Figure 3, the arm 52 is operated by an eccentric 61 mounted on the intermittently operated shaft 62, the eccentric coacting with a face 63 on the power lever 52. The power lever is caused to follow the cam or eccentric 62, during the opening of the press by a spring 64.

Both forms of pressing machines embody a periodic clutch mechanism operable to close the press by a solenoid or electromagnet and the control of the clutch mechanism by a solenoid or electromagnet.

The control of the opening and closing of a garment and laundry press having two movements, one a closing movement and the other an opening movement, is the essential feature of this invention.

What I claim is:

1. In a pressing machine the combination of cooperating pressing elements, one movable toward and from the other, mechanism for applying pressure to the movable element comprising a constantly rotating driving member, an intermittently movable driven member, a periodic clutch for connecting the driving and driven member, the clutch comprising a section normally out of clutching position and shiftable into clutching position, a spring for shifting the clutch out of clutching position, controller means having a surface for holding the section in its clutched position against the action of the spring after the section has been shifted initially into clutched position when the press is closed, and means for controlling the initial shifting of the section to clutched position when the press is open or closed including an electromagnet, and a plurality of normally open, manually closable switches in the circuit of the magnet.

2. In a pressing machine the combination of cooperating pressing elements, one of which is movable toward and from the other, means for moving the movable element to close the press and apply pressure to the movable element, and to open the press, and controlling means for said mechanism comprising an electromagnet and a plurality of manually operable normally open switches, the switches being connected in series in the circuit of the electromagnet, and means for controlling the opening movement of the press independently of the electromagnet after the electromagnet has been momentarily energized by the closing of the switches.

3. In a garment or laundry pressing machine in combination cooperative pressing

elements one of which is movable with respect to the other; operating mechanism for the movable pressing element; a power means; a clutch for connecting the power means with the operating mechanism; a pair of manuals for controlling the clutch, both of which must be operated to cause the clutch to engage; and means operable upon release of either of said manuals, during closing movement of the press, for disengaging the clutch so that the closing movement will stop.

4. In a garment or laundry pressing machine in combination cooperative pressing elements one of which is movable with respect to the other; operating mechanism for the movable pressing element; a power means; a clutch for connecting the power means with the operating mechanism; a pair of manuals for controlling the clutch, both of which must be operated to cause the clutch to engage; means operable upon release of either of said manuals, during closing movement of the press, for disengaging the clutch so that the closing movement will stop; and means to immediately return the press to open position when the closing movement is thus interrupted by release of one of the clutch control manuals.

5. In a garment or laundry pressing machine in combination cooperative pressing elements one of which is movable with respect to the other; operating mechanism for the movable pressing element; operator operated electric means for controlling the operating mechanism to open and close the press; mechanism to render the operating means ineffective if the operator operated means is released; and means to prevent operation of said mechanism during the opening movement of the press.

6. In a garment or laundry pressing machine in combination cooperative pressing elements one of which is movable with respect to the other; operating mechanism for the movable pressing element including a shiftable clutch for connecting the operating mechanism with a power source; electrically operated control means for engaging the clutch to open and close the press; and means for disengaging the clutch upon release of said electrically operated control means during the closing of the press.

7. In a garment or laundry pressing machine in combination cooperative pressing elements one of which is movable with respect to the other; operating mechanism for the movable pressing element including a shiftable clutch for connecting the operating mechanism with a power source; electrically operated control means for engaging the clutch to open and close the press; means for disengaging the clutch upon release of said electrically operated control means during the closing of the press; and means to prevent operation of

the clutch disengaging means during the opening of the press.

8. In a garment or laundry pressing machine in combination cooperative pressing elements one of which is movable with respect to the other; operating mechanism for the movable pressing element; a constantly running electric motor; a clutch for connecting the electric motor with the operating mechanism; electrically operated means for controlling the clutch including a pair of manually operated switches, both of which must be closed to cause the clutch to engage; means normally holding said switches in open position; and means operable upon release of either of said switches, during closing movement of the press, for disengaging the clutch so that the closing movement will stop.

9. In a garment or laundry pressing machine in combination cooperative pressing elements one of which is movable with respect to the other; operating mechanism for the movable pressing element; a constantly running electric motor; a clutch for connecting the electric motor with the operating mechanism; electrically operated means for controlling the clutch including a pair of manually operated switches, both of which must be closed to cause the clutch to engage; means normally holding said switches in open position; means operable upon release of either of said switches, during closing movement of the press, for disengaging the clutch so that the closing movement will stop; and means to immediately return the press to open position when the closing movement is thus interrupted by release of one of said switches.

In testimony whereof, I have hereunto signed my name, at Syracuse, in the county of Onondaga, in the State of New York, this 26th day of June, 1924.

PHILIP N. BRAUN.
